UNITED STATES PATENT OFFICE

JAMES B. HOLTSON, OF BALTIMORE, MARYLAND, ASSIGNOR TO THE HUFFMAN MANUFACTURING COMPANY, OF DAYTON, OHIO, A CORPORATION OF OHIO

TANK VENT DEVICE

Application filed March 3, 1927. Serial No. 172,428.

This invention relates to accessories for use in connection with storage tanks for combustible liquids, particularly gasoline or other similar fuels, lubricating oils and the like.

It is well known that the tanks commonly provided at automobile service stations and many other places for the storage of gasoline and lubricating oils, and storage tanks for liquid fuel for domestic and industrial burn-

ers are usually underground and provided with certain inlet means whereby the supply

therein may be replenished from time to time. It is also known that it is customary to provide a vent device whereby air within

the tank may escape when liquid is introduced, and whereby air may be permitted to pass in or out in accordance with its expansion or contraction within the tank responsive to temperature variations. Regardless

of whether the tank be located above or below ground or whether it be stationary or mounted upon a car or other wheeled vehicle, venting means of some character is necessary. It is also necessary that the vent device be of such construction as to embody a wire screen or gauze which will operate to prevent any flame, resulting from any cause, from entering the tank and exploding the contents.

It is with the above facts in view that I have designed the present invention which has for its general object the provision of a novel or improved vent device embodying a flame checking screen or gauze and provided with easily applicable means for maintaining the gauze in position while permitting it to be removed in case of necessity, as for instance cleaning purposes, said maintaining means being of a clamping nature so as to avoid the use of solder which would melt and permit dropping out of the screen in case of fire when its presence is most needed.

Another object of the invention is to provide a vent device of such construction that the elements or portions thereof establishing communication between the atmosphere and the interior of the tank in connection with which it is used are so arranged and located as to permit free circulation of air while preventing the ingress of rain, snow or dirt.

A further object of the invention is to

provide a vent device of this character consisting of the minimum number of parts so as to be extremely simple and inexpensive to manufacture, the construction being moreover of such character that the device may be quickly and easily mounted upon or removed from a vent pipe and assembled or disassembled as occasion may require, the device being furthermore positive in action, efficient and durable in service, and a general improvement in the art.

With the above and other objects and advantages in view, the invention preferably consists in the arrangement and combination of parts and detailed structural features to be hereinafter more fully described and claimed, and illustrated in the accompanying drawings in which:

Figure 1 is a side elevation of the preferred form of the invention showing it mounted upon a fragment of a vent pipe,

Figure 2 is a vertical longitudinal section,

Figure 3 is a bottom plan view with the vent pipe in section.

Referring more particularly to the drawings, the numeral 1 designates an upstanding vent pipe which leads from a storage tank, not shown, for liquids such as fuels and oils of various kinds. The device itself is designated generally at 2 and preferably comprises a single elongated shell 3 conveniently formed as a casting. The shell has its bottom open except for a central portion 4 which is apertured at 5 and threaded for connection with or mounting upon the pipe 1. The provision of this central portion 4 defines openings 6 at the opposite end portions of the underside of the device, these openings being here shown as of rectangular shape with rounded corners though there is naturally no limitation as to the specific configuration.

To prevent danger of explosion of any gases in the tank and vent pipe, I provide wire screen or gauze members 7 located at the openings 6 so as to cover the same and be in the path of any air passing to or from the tank. While it is conceivable that different means might be provided for the purpose of holding these screen members in place, I prefer to employ retaining means formed as

open frame members 8 of such size and shape as to be received within the openings 6 with the screen wire jammed or compressed between the sides of these frame members and the adjacent walls of the openings 6. The members 8 are provided with outstanding flanges 8^a which overlie the edges of the openings 6 so as to prevent the members 8 from being forced too far into the shell when the parts are assembled.

In the operation it will of course be apparent that when the tank is filled the air therein displaced by the inflowing liquid will pass through the pipe 1, into the shell 3 and out through the open frame members 8. If the air or gas within the tank expands as it will during a rise in temperature the air will pass out in the same manner, and in case of contraction as the result of a lowered temperature air may enter the tank through the device. In view of the fact that the screens 7 are located in the path of any air currents to or from the tank and as it is well known that a flame will not pass through a screen of proper mesh, any danger of explosion will be avoided.

From the foregoing description and a study of the drawings it will be apparent that I have thus provided a simply constructed, inexpensive and easily applied vent device which will operate efficiently to prevent explosion of any gases accumulating within the storage tank in connection with which it is used. In view of the fact that the openings 35 for the ingress or egress of air are located at the underside there will be no opportunity for rain water, snow or foreign matter of any kind to enter. Any dirt blown in will of course be stopped by the screen or gauze. If, 40 in the course of time, it should ever become necessary to clean the screen or screens, it is obvious that the screen retaining elements may be detached to permit removal and replacement of the screens in a very simple and 45 expeditious manner.

A distinct feature of advantage is that the wire screen or gauze is held in place simply by clamping means there being no solder whatsoever used. This detail is in accordance 50 with the requirements of the underwriters who prohibit the use of solder for the reason that such will melt and permit the screen to drop out in case of fire when the presence of the screen is most urgently required. The 55 clamping means will maintain its holding action regardless of any heating effects and the device will be consequently safe under any and all conditions.

While I have shown and described a preferred embodiment of the invention, it should be understood that the disclosure is simply an exemplification of the general principles involved and that the right is reserved to make such changes in the details of construction 65 and the arrangement and combination of

parts as will not depart from the spirit of the invention or the scope of the appended claim.

Having thus described the invention, I claim:

A tank vent device comprising a single integral hollow body with a convexly curved top and a plane flat bottom, the bottom being formed with a central opening adapted to receive a pipe and being further formed with other openings located near the ends, sleeve members telescopically engaged within the second named openings, and wire screen covering said second named openings and frictionally held in place by said sleeve members.

In testimony whereof I affix my signature.

JAMES B. HOLTSON.
